UNITED STATES PATENT OFFICE.

JOHN E. BELL, OF NEW YORK, N. Y., ASSIGNOR TO THE BABCOCK & WILCOX COMPANY,
OF NEW YORK, N. Y., A CORPORATION OF NEW JERSEY.

SUPERHEATER-BOILER.

1,077,117.

Specification of Letters Patent.

Patented Oct. 28, 1913.

Application filed May 31, 1906. Serial No. 319,457.

To all whom it may concern:

Be it known that I, JOHN E. BELL, a citizen of the United States, residing in New York, in the county and State of New York, have invented a new and useful Improvement 5 in Superheater-Boilers, of which the following is a full, clear, and exact description, reference being had to the accompanying drawing, forming part of this specification, in which the figure is a sectional side 10 elevation showing one form of my improved superheater-boiler.

My invention relates to the applying of superheaters to water tube boilers having a 15 plurality of banks of vertically extending tubes in series, as regards the passage of the furnace gases; and its object is to combine a superheater, particularly one of U-shape type, with such a boiler in such a way as to give economical results and good efficiency, 20 while avoiding difficulties heretofore incident to the use of superheaters in such types of boilers.

In the drawing, 2, 3 and 4 represent upper 25 transverse steam and water drums connected by vertically inclined tubes 5, 6 and 7 to the lower transverse mud drum 8.

9 is the furnace, the flame and gases from which are directed among the tubes of the 30 front bank by the baffle 10 extending along its rear and preferably having a shelf 11. The gases flow down from the top of the front bank over the second bank to the bottom of the baffle 12, whence they arise 35 through the last bank of tubes and pass out to the outlet port 13.

The superheater, which is of the inverted U-tube type, is shown as consisting of boxes or headers 14 and 15 preferably located under the shelf 11, if such is used. These boxes 40 extend across the setting between the side walls and are exposed to the hot gases circulating through the second pass. From them extend upwardly the U-shaped superheater tube 16, the bends of which are preferably below the water circulators 18 extending between the water spaces of the steam and water drums 3 and 4 below the refractory partition 17. The superheater tubes 45 are preferably inclined upwardly and forwardly in the general direction of the water tubes and I have shown the steam as led

from the front drum 4 into the middle drum 3 through pipes 20, any steam generated in the front drum 2 also passing in the middle 55 drum through tubes 19. The steam in this form is taken from the middle drum through pipe 21 to one of the boxes, preferably the upper box 14, whence it flows through the U-shaped tubes to the other box and is taken off through the outlet pipe 22. In this location of the U-tube superheater, the tubes and the boxes or headers are more or less exposed to the flaming action of the furnace and to the hot gases. A fairly high degree 65 of superheat may therefore be obtained, while, at the same time, the superheater is readily accessible. Injury to the expanded joints, when these are used between the superheater tubes and the boxes, is prevented by the fact that the flame and gases strike the upper parts of the superheater tubes before reaching the boxes. The boxes or headers form a superheating surface, while injury to the joints is avoided. The 70 inverted U-tube superheater gives good drainage for condensation; and interference with the water circulating tubes, where these are used, is avoided. The superheater 75 may be placed in the second pass, since the temperature of the gases is reduced by the water tubes and the superheating tubes sufficiently to prevent injury to the headers and joints therein. The headers thus serve as the superheater supports, avoiding special supporting devices which might be injured by the high temperature. Expansion and contraction of the superheating tubes is taken up in the tubes and does not injure the expanded joints or force the headers out of place. As 80 the U-tubes extend in a general vertical direction there are no excessive side strains on the joints between them and the headers, which might cause them to sag under the high temperatures. The complication due to 85 placing headers in the walls of the setting or outside is done away with and the headers give additional superheating surface.

The superheater is of low cost, is simple in construction and may be easily reached 100 for inspection and repair. The shelf at the rear of the baffle, where used, may be varied in width to regulate the superheat.

The superheater does not interfere with

the standard type of boiler, nor require any change in design. It can also be readily applied to existing boilers.

A number of mud drums may be used, 5 two or more banks of water tubes may be employed, and many other changes may be made without departing from my invention.

I claim:

1. The combination with a water tube 10 boiler having a plurality of banks of vertically extending tubes in series as regards the passage of the furnace gases, separated by a baffle over which the gases flow in passing from the front bank to the next, of a 15 superheater between said banks of tubes comprising a plurality of headers behind said baffle connected by superheating tubes extending upwardly from the headers.
2. The combination with a water tube 20 boiler having a plurality of banks of vertically extending tubes in series as regards the passage of the furnace gases, of a baffle back of the front bank of tubes, and an inverted U-tube superheater in the rear of 25 said baffle and between the first and second bank of tubes.
3. The combination with a water tube 30 boiler having a plurality of banks of vertically extending tubes in series as regards the passage of the furnace gases, of a superheater between the first and second banks of tubes, said superheater comprising headers or boxes extending between the side walls of the setting and connected by superheating tubes extending upwardly therefrom.
4. The combination with a water tube 35 boiler having a plurality of banks of vertically extending tubes in series as regards the passage of the furnace gases and having at least two steam and water drums with water circulators between them, of a superheater back of the baffle for the front bank and comprising a plurality of cham-

bers between the side walls and connected 45 by superheating tubes extending upwardly therefrom.

5. The combination with a water tube boiler of the general Stirling type having a triangular space between the first and second 50 banks, of an inverted U-tube superheater located in the upper portion of said triangular space, and having headers extending across from side wall to side wall and exposed to the products of combustion. 55

6. The combination with a water tube 60 boiler having a plurality of banks of vertically extending tubes in series as regards the passage of the furnace gases, separated by a baffle over which the gases flow in passing from the front bank to the next, said baffle having a rearwardly projecting shelf, of a superheater between said banks of tubes comprising a plurality of headers behind 65 said baffle and below the level of said shelf, said headers being connected by superheating tubes extending upwardly from the headers.

7. The combination with a water tube 70 boiler having a plurality of banks of vertically extending tubes in series as regards the passage of the furnace gases, separated by a baffle over which the gases flow in passing from the front bank to the next, of a superheater between said banks of tubes 75 comprising a plurality of chambers behind said baffle, said headers being connected by superheating tubes which extend upwardly from the headers and are inclined forwardly in the general direction of the water 80 tubes.

In testimony whereof, I have hereunto set my hand.

JOHN E. BELL.
